UNITED STATES PATENT OFFICE.

JAMES C. DRAKE, OF ROCHESTER, MINNESOTA, ASSIGNOR TO SEARS, ROEBUCK AND COMPANY, OF CHICAGO, ILLINOIS, A CORPORATION OF NEW YORK.

SOUND-BOX MOUNTING FOR TALKING-MACHINES.

1,385,118.

Specification of Letters Patent.

Patented July 19, 1921.

Original application filed April 17, 1917, Serial No. 162,747. Divided and this application filed February 19, 1920. Serial No. 359,947.

To all whom it may concern:

Be it known that I, JAMES C. DRAKE, a citizen of the United States, residing at Rochester, in the county of Olmsted, State of Minnesota, have invented certain new and useful Improvements in Sound-Box Mountings for Talking-Machines, of which the following is a specification, reference being had therein to the accompanying drawing.

10 My invention relates to sound recording and reproducing machines and especially sound box mountings therefor.

An object of my invention is to provide a simple and effective arrangement for mounting a sound box upon the tone arm of a machine of the above type.

I attain my object in the following manner: I provide the tone arm with a short terminal tube, which is pivoted to the arm 20 to have play upward and downward with respect thereto. This tube receives either one of two short adapters or attachments, to which the sound box is attached.

One end of each adapter is provided with 25 a neck, and a guide working in a slot, in the collar attached to the sound box. The other end of each adapter has a radially projecting screw attached to it, and upon the screw a nut with knurled edge to be turned by the 30 fingers without a tool, the inner face of the nut being concave. This end of the adapter fits in the end of the terminal tube on the tone arm, which said tube is provided with a single slot to receive the screw on the 35 adapter, and on both sides of the slot a convex projection fitting the inner concave face of the nut, so that the nut when screwed down clamps the adapter on the tube end, while the slot serves as a guide and determines the correct angular position of the 40 adapter on the tube.

This application is a division of my co-pending application filed April 17, 1917, Serial No. 162,747.

45 My invention is illustrated in the accompanying drawings in which:

Figure 1 is a top plan view of a portion of a tone arm with one form of sound box connecting elbow or adapter attached and 50 with the sound box removed;

Fig. 2 is a side elevation of the same with sound box attached;

Fig. 3 is a fragmentary side view of the

jointed end of the tone arm showing the guide slot and convex projections;

Fig. 4 is a top plan view of the elbow adapter shown in Fig. 1 but removed from the tone arm;

Fig. 5 is a side view of the adapter of Fig. 4;

Fig. 6 is a side view of the sound box mounting assembled with the adapter for playing vertically cut records, its screw being at right angles to that of Figs. 1 and 4, with respect to the sound box.

Fig. 7 is a section on the line $x-x$ of Fig. 1.

Referring to the details of the drawings, 1 indicates the body of the tone arm. The hollow tone arm 4 communicates with a suitable horn or amplifier not shown. The tone arm is provided at its free end with a short pivoted tubular section 5 forming the terminal of the tone arm proper. This tone arm terminal 5 is provided with a laterally projecting double convexity or stud 6 and is split or slotted at 7, the slot passing between the two convexities 6. By the provision of the slot 7 a certain amount of expansion of the circumference of the end of 80 the section 5 is afforded, and to increase the expansibility of the tube at this locality, I reduce the thickness of the wall of the tube as indicated at 8 from the free end inward to a depth slightly greater than that of the 85 slot 7, as indicated by the dotted line 9. Preferably the convexities 6 are embossed in the tube 5, although it may of course be cast or soldered or otherwise formed upon the tube.

90 For the purpose of connecting the sound box to this tone arm terminal 5, I provide a pair of interchangeable elbow adapters 10 and 11, shown also in Figs. 4, 5 and 6, which elbows vary somewhat in length and angular adjustment. This variation, as stated, is for the purpose of connecting the same sound box, or sound boxes of the same type, with the tone arm in different angular relations thereto according to the type of record to 100 be played. For example, the adapter 10 is for use with records of the laterally undulating groove type, while the adapter 11 (Fig. 6) is for use with records of the perpendicularly-undulating-groove type. 105 In Figs. 1 and 2, I have shown the adapter

10 in operative connection with the tone arm terminal 5, Fig. 1, without the sound box, and Fig. 2 with the sound box 12. The adapter 10 consists of a tube bent in the 5 form of a rectangular elbow having one end reduced as at 13 to fit within the tone arm terminal 5 and forming a shoulder 14. Mounted on the reduced portion 13 and projecting outwardly and radially therefrom 10 is a screw 15 which is held fixed in the elbow, preferably by a soldered head 16. This screw is of such diameter as to enable it to pass into the slot when the reduced end 13 of the elbow is passed into the tone arm terminal 5 and is so spaced from the shoulder 14 that upon the engagement of the shoulder with the end of the tone arm terminal, the said shank will be positioned in the slot concentrically with the convexities 6. A lock 15 nut 17 is carried by the screw in threaded engagement therewith and is provided with a concavity 18 on its inner surface for engagement with the convexities 6. (See particularly sectional Fig. 7). The engaging 20 surfaces of the parts 5 and 13 are so proportioned in relation to each other that their engagement causes a slight distortion or expansion of the slotted end of the member 5 so that the resiliency of the reduced portion 25 30 35 40 45 50 55 60 65 70 75 80 85 90 95 100 105 110 115 120 125 130 135 140 145 150 155 160 165 170 175 180 185 190 195 200 205 210 215 220 225 230 235 240
